WATER CLOSET BOWL

Gordon P. Gavin, Kohler, Wis.

Application June 7, 1935, Serial No. 25,367

3 Claims. (Cl. 4—69)

My invention relates to improvements in water closet bowls, and the object of my invention is to provide a water closet bowl of a construction such that it is impossible under any conditions 5 to remove any of the water from the bowl by back syphoning.

I attain this object by the construction illustrated in the accompanying drawing, in which Figure 1 is a plan view, certain parts being broken 10 away to show the interior construction, of a water closet bowl constructed in accordance with my invention, and Figure 2, a vertical sectional view along the lines 2—2 of Figure 1.

Similar numerals refer to similar parts 15 throughout the several views.

The water closet bowl, designated generally by the numeral 1, may be of any suitable construction, such as, for example, that shown in the illustration.

20 The water closet bowl 1 is formed into a water retaining space or well 2 extended rearwardly to form the dam 3 which, together with the downwardly extending dam 4 forms the up leg of a syphon-discharge passageway the down leg of 25 which is designated by the numeral 5.

The dam 3 is of sufficient height to retain water in the well 2 to a point where the lowermost portion of the dam 4 will be immersed therein, thus providing a water seal and preventing the return 30 of gases from the discharge pipe or sewer. A water inlet 6 in the top of the bowl, adapted to receive a spud or other means for connection to a water supply pipe, discharges into a reservoir 7.

35 Channels 8 extend downwardly on opposite sides of the syphon discharge passageway and communicate with the chamber 9. A jet 10 extends between the chamber 9 and the well 2 and is adapted to discharge into the up leg of the syphon discharge passageway to facilitate the 40 syphon action.

The bowl is likewise provided with the flush rim 11 having the usual channel 12 and flush holes 13 spaced about the lower side of said rim and adapted to discharge water downwardly into 45 said bowl to cleanse the sides thereof.

The channel 14 provides communication between the reservoir 7 and the channel 12 of the flush rim 11. It will be noted that the channel 14, channel 12 and flush holes 13 form a continuous passageway from the reservoir 7 to the 50 interior of the bowl.

Thus upon flushing of the bowl water is delivered from a flush tank or flush valve, through inlet 6 to reservoir 7 and thence, simultaneously, 55 to jet 10 through passageways 8 and chamber 9

and to the rim flush holes 13 through channels 14 and 12.

The construction thus far described is a conventional one. However, it has a serious disadvantage in that, if for any reason such as failure 5 of the water supply, a vacuum instead of a pressure be developed in the water supply line, the reverse action takes place and the water is syphoned from the bowl into the supply line where it becomes commingled with and contaminates the drinking water supply of the building.

I propose to remedy this defect and prevent back syphoning of the water in the bowl under any conditions by providing an air inlet to the 15 reservoir 7 which air inlet is above any possible level of the water in the bowl and will prevent any syphon action from developing by admitting air through the reservoir 7, thus preventing any vacuum in the supply line from being effective 20 to syphon the water from the bowl.

In the preferred form of construction shown in the illustration communication between the reservoir 7 and the exterior atmosphere is obtained through channels 14, 12 and flush holes 13. 25

Thus, in case of a vacuum developing within the supply line, air is admitted to the reservoir 7 to equalize the pressure and eliminate the vacuum with its attendant syphoning effect.

When water is supplied under pressure to reservoir 7, as during flushing of the bowl, this channel acts as a discharge passageway, hence the 30 operation and efficiency of the bowl is not impaired.

As will be seen from Figure 2, flushing rim 11 35 is higher at the rear of the bowl than at the front, and the channel 14, together with one or more of the flush holes 13, is above the level of the lowest point of the top of the flushing rim 11, represented in Figure 2 by the lines A—A.

Hence it is impossible for the water level of the bowl, even in the case of clogging of the syphon discharge passageway, to rise sufficiently to seal the channel 14 and its adjacent rim flush holes, since the water will overflow the flushing 45 rim 11 at its forward and lowermost point before it reaches a height sufficient to seal the channel 14 and the adjacent rim flush holes.

It will be evident that changes in the exact construction disclosed may be made without invention, such as, for example, providing an overflow 50 separate from the flushing rim or placing the lowermost point of the flushing rim in a different location; hence I do not restrict myself to the exact construction illustrated, but claim all 55

constructions within the spirit of my invention and the scope of the appended claims.

I claim:

- 5 1. A water closet bowl comprising, in combination, a siphon discharge passageway terminating in a well adapted to retain water to provide a water seal, a jet adapted to discharge into said siphon discharge passageway, a reservoir positioned above the water level in said well, a water 10 inlet to said reservoir, a channel providing communication between said reservoir and said jet, a flushing rim positioned above the water level in said well and completely enclosed except for a plurality of flush holes therein and a channel providing communication between said reservoir and said flushing rim, the channel providing communication between said reservoir and said flushing rim at its lowermost point said reservoir being completely 15 enclosed except for said inlet, said jet communicating channel and said flushing rim communicating channel.
- 20 2. A water closet bowl comprising, in combination, a reservoir, a water inlet thereto, a flushing rim, a channel providing communication between said reservoir and said flushing rim, and means for providing communication between said channel and the exterior atmosphere, said channel and said communicating means being positioned above the top of said flushing rim at its lowermost point the water from said reservoir being 25 discharged into said bowl only from said flushing rim and a jet positioned below the normal water level of said bowl.

rim, a channel providing communication between said reservoir and said flushing rim, and a plurality of flush holes in said flushing rim, the channel providing communication between said reservoir and said flushing rim and one or more of said flush holes being above the level of the top of said flushing rim at its lowermost point said reservoir being completely enclosed except for said inlet, said flushing rim communicating channel and a channel communicating with a jet positioned in said bowl.

3. A water closet bowl comprising, in combination, a reservoir, a water inlet thereto, a flushing rim, a channel providing communication between said reservoir and said flushing rim, and means for providing communication between said channel and the exterior atmosphere, said channel and said communicating means being positioned above the top of said flushing rim at its lowermost point the water from said reservoir being discharged into said bowl only from said flushing rim and a jet positioned below the normal water level of said bowl.
